UNITED STATES PATENT OFFICE.

LUCIUS H. HOYT, OF DANBURY, CONNECTICUT.

APPARATUS FOR CURLING AND SETTING HAT-BRIMS.

SPECIFICATION forming part of Letters Patent No. 314,131, dated March 17, 1885.

Application filed June 23, 1884. (No model.)

To all whom it may concern:

Be it known that I, LUCIUS H. HOYT, of 5
Danbury, Fairfield county, in the State of
Connecticut, have invented certain new and
useful Improvements in Apparatus for Curling
and Setting Hat-Brims, of which the following
is a specification.

I have discovered that a continuous sheet of
vulcanized india-rubber of moderate thick- 10
ness extended over the metallic parts which
constitute the adjustable forming-surface will
expand and contract by its elasticity, so that
a single covering-sheet will serve for many
variations in the sizes of the hats and in the
15 breadths of the brims, and will so cover and
conceal the joints in the metal portions that
the latter may be formed as overlapping parts
sliding one upon another, and the changes of
dimensions will be so induced.

20 I have in Letters Patent to me dated June
3, 1884, No. 299,644, shown a hat setting ma-
chine having metallic parts thus organized
and working. The machine as there described
is useful; but a difficulty is involved in the
25 fact that the several plates of metal to pos-
sess the proper strength and rigidity must
have considerable thickness, and, as the edge
of one overlaps more or less upon the surface
30 of another, in the expanding and contracting
of the diameter and in the change of breadth
of the brim they tend to make ridges or lines
where the shape is imperfect.

According to my present invention a single
35 covering-sheet of vulcanized india-rubber ex-
tends over the whole upper surface of the
shaping parts in a smooth continuous sheet.
As the brim-shaping parts are expanded or
40 contracted this sheet by its elasticity corre-
spondingly expands and contracts. The rigid
parts overlap on each other to various degrees.
No matter where the edges of the uppermost
45 overlapping parts come, the india-rubber cov-
ering-sheet of only from a sixteenth to an eighth
of an inch in thickness conceals and disguises
the joint, so that it is not appreciable in its
effect on the hat-brim which is shaped on the
50 upper surface of the rubber thus extended.

A patent to Smith and Hall, dated Septem-
ber 12, 1882, No. 264,420, sets forth hat-shap-
55 ing apparatus in which an india-rubber sur-
face is presented on which the hat is shaped;
but this comes far short of the point attained

by mine. In the Smith and Hall patent the
metallic parts do not overlap, but are sepa- 55
rated by joints which are entirely open. The
rubber is not of uniform or approximately uni-
form thickness, but is formed with ribs which
match in the open joints. Smith and Hall's
device cannot be changed in dimensions ex- 60
cept by opening a joint wider than the rib or
ridge of rubber which is intended to fill it,
thus leaving the joint only partly filled and
the rubber which extends across the joint badly
supported, or, on the other hand, closing the 65
joint so that it is thinner than the rubber ridge,
the rubber being previously introduced into
place and the metal parts brought together by
powerful means, so as to forcibly compress the
ridge of rubber. When the Smith and Hall 70
apparatus is open wide, so that the rubber
sinks at the joints, it tends to make a bad
place in the hat by the hat sinking too low
along the line of joint. When it is closed up,
so that it much compresses the ridge of rub- 75
ber, it tends to make a bad place in the hat
by the rubber being squeezed upward and
correspondingly lifting the hat along those
lines.

My invention allows a wider range of ex- 80
pansion and contraction of the metallic parts,
and provides a practically even surface on
which the hat may be treated without show-
ing the lines or areas of defective shaping in
any of the conditions.

The following is a description of what I 85
consider the best means of carrying out the
invention.

The accompanying drawings form a part of
this specification.

Figure 1 is a longitudinal vertical section 90
showing the apparatus complete. Fig. 2 is a
corresponding plan view with a portion of
the rubber covering broken away to show the
overlapping shaping parts. Fig. 3 is a ver- 95
tical section through the rubber alone. Fig.
4 is on a larger scale. It is a section through
the overlapping joint between two of the me-
tallic parts, with a portion of the rubber cov-
ering fitting thereon, and concealing (and pre-
venting any ill effect from) the irregularity 100
in the surfaces thus produced.

Similar letters of reference indicate cor-
responding parts in all the figures.

I will describe the invention as applied

with the overlapping rigid parts as set forth in the patent to me, No. 299,644, dated June 3, 1884; but it will be understood that these parts and the means for operating them may 5 be varied within wide limits so long as the shaping parts are overlapping parts, and adjustable on each other by changing by any suitable means the extent to which they thus overlap.

10 I is the inner shaping-piece, and J the outer shaping-piece.

M is the outer side-shaper and R the inner side-shaper.

15 The means for stiffly supporting and adjusting these rigid metallic parts I J M R may be as set forth in my said patent of June 3, 1884, and need not be particularly described here.

20 My india-rubber covering is marked Y, portions being distinguished when necessary by additional marks, as Y' Y''. A continuous smooth portion, Y', extends over the upper face of the shaping parts I J M R. An approximately cylindrical portion, Y'', extends downward from the inner edge of Y'.

25 Y³ is an extension inward from the outer edge of Y'.

I have in my experiments made the portion Y' about one and three-quarters (1 $\frac{3}{4}$) inch wide, and about three thirty-seconds ($\frac{3}{32}$) of 30 an inch thick; and the inner part, Y'', about three inches deep and a sixteenth of an inch thick at the upper edge, increasing at about half its depth to an eighth of an inch thick; and I have made the inwardly-extending portion Y³ about an eighth of an inch thick, the extension inward and downward of the part Y² being sufficient to reach nearly or quite to the metallic parts which lie adjacent to the hat-crown. The entire piece Y is preferably 35 made in a single piece of vulcanized rubber; but I believe it may be made to serve by piecing.

40 Instead of pure vulcanized rubber, ordinary adulterants may be used, giving firmness and 45 body with economy; but it is important to retain a large amount of the peculiar elastic quality which is so conspicuous in pure rubber, in order that the dimensions of the hat-body and the breadth of the brim may be varied within wide limits by the simple extensibility and contractility of the covering Y, the latter being smooth and applying close to 50 the metallic parts in all conditions.

I will term the material "rubber," and I prefer that it be nearly pure rubber, worked 55 with the right proportions of sulphur, and vulcanized to constitute soft vulcanized rubber.

It will be obvious that the rigid parts I J, &c., may be made with widely-varying degrees of curvature, so as on the one hand to shape 60 brims which are nearly plane, or, on the other hand, brims which have very great curvature or "scope" without requiring any change of the elastic covering Y.

65 In collapsing or closing together the hard metallic parts to remove a hat after shaping the rubber covering Y may become slackened and lose its proper shape; but after applying a fresh hat and properly expanding the metallic parts the rubber is sure to be drawn into 70 a smooth-fitting condition, so it is certain to be smooth and shapely at the periods while it is wanted.

75 I have demonstrated by trial that a continuous sheet of rubber of a thickness of only about a sixteenth of an inch is sufficient to avoid the offensive marking by the edges of the lapping part and allow the hat-brim with the gentle force of the hands or other pressure to be shaped thereon smoothly and uniformly.

80 When the rubber is applied in the correct position, it may be confined by any suitable means applied, preferably, at or near the lower edge, Y².

I claim as my invention—

85 1. The elastic covering described, composed of soft vulcanized india-rubber having a cylindrical portion, Y'', upper or working face, Y', and inward extension Y³, adapted to serve on a hat-brim shaper, as herein specified.

90 2. In a hat-brim shaper, the combination, with properly-formed overlapping rigid parts, as I J, a covering-piece, Y, of india-rubber or analogous elastic material, contracting and expanding by its own elasticity as the rigid parts are lapped more or less, as herein specified.

95 In testimony whereof I have hereunto set my hand, at Danbury, this 16th day of June, 1884, in the presence of two subscribing witnesses.

LUCIUS H. HOYT.
